UNITED STATES PATENT OFFICE

HERMAN TEETOR, OF HAGERSTOWN, INDIANA, ASSIGNOR TO THE PERFECT CIRCLE COMPANY, OF HAGERSTOWN, INDIANA, A CORPORATION OF INDIANA

PISTON AND PISTON RING FOR INTERNAL COMBUSTION ENGINES

Application filed June 16, 1930. Serial No. 461,317.

My invention relates to pistons and piston rings for internal combustion engines and more particularly to that type of ring known as "oil rings" which are employed to remove excess oil from the cylinder walls and permit it to return to the crank case of the engine.

The principal object of my invention is to provide a novel oil ring having elongated slots and a continuous groove in its inner or back face with which the inner ends of the slots communicate.

My invention is explained more fully by reference to the accompanying drawings in which:

Fig. 1 illustrates a ring, embodying my invention, applied to a piston of an internal combustion engine, the fragments of the parts being shown in longitudinal cross section; and

Fig. 2 is a plan view of the ring with a small section broken away. The section through the ring as shown in Fig. 1 is taken on the line 1—1 of Fig. 2.

The piston 3 which is adapted to reciprocate in the cylinder 4 of an internal combustion engine, is provided with the usual plain rings 5. The inner groove 6 in the piston is connected to the interior of the piston by drain openings 6^a which permit the oil scraped from the cylinder wall to be returned to the crank case. Seated in the groove 6 is my improved oil ring 7.

My improved ring 7 is provided with elongated slots 8 equally spaced and extending from the exterior face of the ring to a continuous annular compensating groove 9 formed in the interior or back face of the ring. The groove 9 is preferably substantially wider than the slots 8 which preferably have converging ends forming the sides of the generally triangular-shaped parts or bridges 10 between the adjacent ends of the slots. At each bridge, except at the bridges 10^a adjacent the joint or split 12, the groove 9 is provided with a recess 11 to reduce the size of the bridges.

I have found that with a ring having elongated oil slots but no compensating groove, the ring in use does not maintain its true cir-

cular form because the ring is not of uniform cross section, the ring being solid in cross section at the bridges and hollow at the slots. As a result, the bridges cause "high spots" on the exterior face of the ring with attendant excessive wear of the ring and cylinder at those points and greatly impaired efficiency of the ring. The compensating groove substantially overcomes these defects. It materially reduces the size of the bridges, particularly as the groove is formed in the inner face of the ring and the wide base portions of the triangular bridges are cut away when the groove is formed. The recesses 11 still further reduce the bridges in size and make the ring more uniform in cross sectional area so that the ring exerts a substantially uniform pressure throughout its circumference against the cylinder wall. Further, as the groove 9 in the inner face of the ring connects the various slots 8, the oil scraped from the cylinder wall and conveyed through the slots, may be distributed by and along this groove more evenly and drained off through the drain openings in the piston, thus making the ring more efficient than would be the case if no communicating groove were provided.

I claim:

In combination with a piston for an internal combustion engine, having a piston ring groove with apertures extending from the back of the groove to the interior of the piston to permit the draining of oil to the crank case, of a piston ring mounted in the groove and having closely adjacent, elongated slots forming separating bridges triangular in shape and a continuous compensating groove in the interior face of the ring and in the zone of the slots and bridges with recesses formed at the bases of the bridges, the slots extending from the exterior cylindrical face of the ring to the continuous compensating groove.

In testimony whereof, I have subscribed my name.

HERMAN TEETOR.
